4 Claims. (Cl. 72—21)

ABSTRACT OF THE DISCLOSURE

A strip tension control for a tandem rolling mill in which an electrical signal derived from the height of a tension roll positioned vertically against the strip controls the strip tension by varying the speed of the roll stand following the tension roll. In order to maintain tension against the strip during start up, the normal operating source of current for the field of the generator powering the roll motor is replaced during start up by a second source of current through a capacitance-resistance network whose characteristics result in initially moving the tension roll very rapidly to overcome inertia in the mill. When the tension roll approaches normal operating height the second power source is replaced by the normal operating source of current for the generator field.

This invention relates to a strip tension control for a rolling mill and more particularly to a control for a tandem mill for cold rolling steel strip. In such mills it is common practice to provide a horizontal tension or looper roll between the stands of the mill which is movable vertically by means of fluid operated cylinders in order to maintain tension on the strip being rolled. An electrical control signal derived from a transducer whose output is proportional to the height of the tension roll regulates the speed of the roll stand following the tension roll so as to maintain a predetermined height of the tension roll. A valve regulates the pressure in the tension roll cylinder so as to maintain a constant predetermined tension in the strip. In one common control an integrator is provided that initiates a rapid change in the speed of the following stand in response to a rapid change of the tension roll so as to return the tension roll to its operating height. The integrator also provides a cumulative output for a very small input so that a small deviation from the operating height will cause a correction signal that increases with the time until it is large enough to return the tension roll to operating position. When the strip is first threaded through the roll stands the top of the tension roll must be at an elevation at a below the horizontal plane between roll stands. When the automatic control is initiated a very large slow down signal is received and we have found that the tension roll does not move upwardly fast enough to maintain the roll in contact with the strip. When the tension roll loses contact with the strip poor control results.

It is therefore an object of our invention to provide a control which will maintain the tension roll in contact with the strip during start-up as well as during normal operation of the mill.

This and other objects will be more apparent after referring to the following specification and attached drawings, in which:

The single figure is a schematic view of the control of our invention.

Referring more particularly to the drawings, reference numerals 2 and 4 relate to successive stands of a strip rolling mill. Stand 2 is driven from motor 2M and stand 4 from motor 4M. Strip S passes from roll stand 2 to

2

roll stand 4. A looper roll 6 is provided between roll stands 2 and 4 and is adapted to contact the lower side of the strip S. The roll 6 is moved vertically by hydraulic motor 8 having its piston rod 8R connected to the roll 6. Fluid under pressure is delivered to the motor 8 from a hydraulic pump 10 through a solenoid valve 12 connected in conduit 14. Solenoid 12S controls the position of valve 12. A rack 16 is connected to move with roll 6 and is in mesh with a gear 18 which is mechanically connected to selsyn transmitter 20. The output of selsyn transmitter 20 is connected to a demodulator 22. This is a standard piece of equipment consisting of a transformer 24, diodes, resistors and capacitors connected as shown. The function of the demodulator is to change the A.C. signal of transmitter 20 to a corresponding D.C. signal. The output of the demodulator 22 is connected to an integrating amplifier 26 which is also a standard piece of equipment, such as a Westinghouse A-102 amplifier model 457-A-682-GB-1. The output of the integrating amplifier 26 is amplified and connected through a power amplifier 28 to generator field 30F of generator 30. The output of generator 30 is connected to motor 4M. Generator 30 has a second field 30F1 which is connected to D.C. power source L1-L2 through an adjustable resistor 30R. Before starting up operation, the operator manually adjusts resistor 30R to provide a base speed for the roll stand 4. A similar speed control consisting of generator 31, field 31F and variable resistor 31R is also provided for roll stand 2 and any other stands of the mill. After the speed of the stands is so adjusted, the strip S is fed through the mill stands. The parts so far described are conventional.

According to our invention, the demodulator 22 is connected to a bistable amplifier 32, the output of which is connected to a relay coil 34 having a normally closed contact 34C and a normally open contact 34C1. A positive feedback circuit 36 is provided from the output of bistable amplifier 32. The amplifier 32 is a standard piece of equipment and may be part No. 613C-803,804 GO1 shown in Westinghouse Electric Bulletin No. 1L16-800-3A. A relay coil 38 connected across D.C. power lines L1-L2 has a normally open contact 38C located in the feedback circuit 36, a normally open contact 38C1 located in the circuit between amplifier 26 and generator 30F, and a normally closed contact 38C2. A relay coil 40 is also connected across lines L1-L2 in series with switches 42 and 44. Relay coil 40 has a normally open contact 40C connected in parallel with switch 42, a normally open contact 40C1 connected in series with solenoid 12S, a normally closed contact 40C2, normally open contact 40C3, and normally open contact 40C4 connected in series with contact 34C1 and relay coil 38. Contacts 34C, 40C3 and 38C2 are connected in series with one another to field 30F from a 48 volt D.C. power source L3. Resistances 46 and 48 are also connected in series with these contacts. A resistor 50 is connected between resistances 46 and 48 to ground in series with a capacitor 52. Series connected resistor 54 and contact 40C2 are connected in parallel with capacitor 52.

In normal operation, the equipment is set up to provide a predetermined tension on the strip between stands 2 and 4 at a predetermined operating height of the roll 6. During normal operation, the roll 6 will be at this height and the tension on the strip will be that desired. At this time the output of the transmitter 20 will be such that there will be no output from demodulator 22. Assuming that the height of the roll departs from the optimum in a lower direction, the output of selsyn transmitter 20 will be such that a D.C. signal will be produced at the output of the demodulator 22, the magnitude of which is dependent upon the amount of departure from the operating height and of such polarity to cause the

generator 30 to operate the motor 4M to decrease its speed. Decreasing the speed of motor 4M will increase the amount of strip between roll stands 2 and 4 and thus permit the roll 6 to rise to its operating position. If, on the other hand, the roll 6 rises above its operating position, a signal of opposite polarity will be produced at the output of demodulator 22, thus causing the speed of motor 4M to increase and to decrease the amount of strip between the stands 2 and 4. The operation so far described is that of the conventional control.

During start-up of the strip mill, roll 6 must be either at or below the horizontal plane between roll stands 2 and 4. In this position the electrical output signal from demodulator 22 to amplifier 32 is large enough to overcome the effect of the internal bias. The internal bias tends to transfer the bistable amplifier 32 to the "on" state, thus there is no output from amplifier 32. After the strip is threaded through roll stands 2 and 4, it is then necessary that the roll 6 be raised to its optimum operating position as fast as possible. This is accomplished by the controls of our invention. As soon as the strip enters roll stand 4 the operator closes switch 42. This energizes relay coil 40 and contact 40C is closed to maintain the relay coil 40 energized when switch 42 is released. At the same time, contact 40C1 is closed, thus opening valve 12 to permit fluid under pressure to flow from pump 10 to hydraulic motor 8. Also, contact 40C2 opens, contact 40C3 closes and contact 40C4 closes. When contact 40C2 opens, discharge resistor 54 is removed from across capacitor 52. Closing of contact 40C3 completes the path for current from D.C. source L3 through capacitor 52, thus charging the capacitor. The voltage applied to generator field 30F continues to rise, but at a slower rate, until it approaches a maximum when the capacitor 52 is completely charged. Thus, we provide a current supply means having a variable current which increases from a minimum to a maximum with the rate of change being greatest initially so as to rapidly overcome the inertia of the mill. This control enables the roll 6 to maintain contact with the strip S as the amount of strip between roll stands 2 and 4 increases during initial rolling. Thus, the generator 30 will cause motor 4M to slow down, which permits roll 6 to rise. When roll 6 approaches its operating position, the voltage at demodulator 22 decreases towards zero. Slightly before the operating height of roll 6 is reached, the electrical output signal from demodulator 22 becomes small enough to allow the internal bias to transfer the bistable amplifier to the "on" state. The bistable amplifier 32 will then energize relay coil 34, thus opening its contact 34C and closing contact 34C1. Opening of contact 34C removes the charging current from the capacitor 52. Closing of contact 34C1 energizes coil 38, thus closing contacts 38C and 38C1, and opening contact 38C2. Closing of contact 38C ensures continued energization of coil 34 regardless of the position of roll 6. Closing of contact 38C1 and opening of contact 38C2 transfers operation of the control to normal. When the end of the strip being rolled approaches stand 2 the operator opens switch 44. This causes deenergization of coil 40 so as to return its contacts to their original positions. Opening of contact 40C1 removes pressure from motor 8 through valve 12, thus permitting the roll 6 to lower to or below the horizontal pass line. If desired, switches 42 and 44 may be operated automatically by the strip S.

While one embodiment of our invention has been shown and described it will be apparent that other adaptations and modifications may be made without departing from the scope of the following claims.

We claim:

1. In apparatus for rolling strip comprising a first pair of reducing rolls through which the strip passes, a second pair of reducing rolls through which the strip passes from the first pair of rolls, a tension roll between said first and second pairs of rolls over which the strip passes, means for moving said tension roll in a general vertical direction, a motor for driving said second pair of reducing rolls, means for generating an electrical signal proportional to the position of said tension roll with respect to a preset position, an integrating amplifier, means connecting said signal to said integrating amplifier, a generator having a field connected to the output of said amplifier, and means connecting the output of said generator to said motor; the improvement comprising means for supplying current to said generator field to raise said tension roll when strip is first fed through said second pair of rolls, means for cutting off flow of current from said amplifier to said generator field while said last named means is operating, and means operable by said signal when said tension roll reaches said preset position to disconnect said current supplying means from said field and to cause current to flow from said amplifier to said generator field.
2. The apparatus of claim 1 in which said means for supplying current to said generator field to raise said tension roll when strip is first fed through said second pair of rolls supplies a variable current which increases from a minimum to a maximum with the initial rate of change being greatest.
3. The apparatus of claim 1 in which said means for supplying current to said generator field to raise said tension roll when strip is first fed through said second pair of rolls includes a power source, a pair of resistors connected in series from said power source to said generator field, a capacitor, a resistor connected between said pair of resistors in series with said capacitor to said power source, and a resistor connected across said capacitor.
4. The apparatus of claim 3 including a first relay coil having a normally closed contact connected in series with said last named resistor and two normally open contacts one connected in series with said pair of resistors on the power side thereof, means for energizing said first relay coil when strip is first fed through said second pair of rolls, a second relay coil connected in series with the second of said two normally open contacts and having a normally open contact connected between said amplifier and generator field and a normally closed contact connected in series with said pair of resistors on the generator field side thereof, a third relay coil having a normally open contact in series with said second relay coil and a normally closed contact in series with said pair of resistors on the power side thereof, and means operable by said signal when said tension roll approaches said preset position to energize said third relay coil.
